(Cl. D3—19)

To all whom it may concern:

Be it known that we, Clarence A. Pinkham and Bartholomew Holohan, citizens of the United States and residents respectively of Douglaston and Kew Gardens, both in Long Island, in the county of Queens and State of New York, have invented a new, original, and ornamental Design for a Sewing Machine Needle Threading Device, of which the following is a specification, reference being had to the accompanying drawing, forming part hereof, in which:

Fig. 1 is a side elevation of a sewing machine needle threading device, embodying our new design;

Fig. 2 is a top plan view;

Fig. 3 is a bottom plan view;

Fig. 4 is an end elevation of the same, looking from the left of Fig. 1; and

Fig. 5 is an end elevation of the same, looking from the right of Fig. 1.

We claim:

The ornamental design for a sewing machine needle threading device, as shown and described.

CLARENCE A. PINKHAM.
BARTHOLOMEW HOLOHAN.
